UNITED STATES PATENT OFFICE.

JOHN F. WHITE, OF CHICAGO, ILLINOIS.

LOCK.

1,221,938.

Specification of Letters Patent. Patented Apr. 10, 1917.

Application filed June 29, 1916. Serial No. 106,688.

To all whom it may concern:

Be it known that I, JOHN F. WHITE, a citizen of the United States, residing at Chicago, in the county of Cook and State of Illinois, have invented certain new and useful Improvements in Locks, of which the following is a specification, reference being had therein to the accompanying drawing.

This invention relates to an improvement in locking means for doors and is designed more particularly for use in connection with doors for automobiles or carriages.

The invention appertains to that type of lock wherein a pivoted locking bolt is employed which is manually operated, both to locking and unlocking position.

The object of the invention is that of providing the bolt with spring actuated means for progressively advancing the locking face of the bolt into locked or engaged position with the keeper on the door jamb and for locking or maintaining it in such position against rattling or backward deflection.

Locks for doors for carriages and wagons are subject to the variations of the material upon which they are mounted caused by difference in temperature or swelling and locks which are provided with means for holding the locking element in a fixed or single position are objectionable inasmuch as there is no means provided for taking up automatically the loose fit or providing for the variable conditions suggested. The present invention comprehends a lock fastener or securing mechanism which will maintain the locking face of the bolt in close contact with the engaging face of the frame of the keeper, and so irrespective of the variations caused by temperature conditions or wear. Other advantages of the construction presently to be described will be readily appreciated.

In the drawings there is shown a convenient and desirable form of lock having the different advantageous characteristics, but it is to be understood that in addition to the modifications of operating means shown other means may be employed without departing from the general nature and principle of the invention.

In the drawings:

Figure 1 is a sectional view of the improvement showing the rocking locking bolt in its position for securing the doors closed; Fig. 2 is a section showing parts in eleva-

tion of means for operating the bolt securing means from either side of the door;

Fig. 3 is an elevation of the inside operating means shown in Fig. 2;

Fig. 4 is a slight modification of an operating means;

Fig. 5 is an elevation of the lock showing a different form of operating mechanism;

Fig. 6 is a section through the door showing a still further form of operating mechanism for the lock securing means;

Fig. 7 is a detail perspective of the keeper, and,

Fig. 8 is a section through the lock showing the preferred form of instrumentalities for operating the lock to set and maintain the same in its proper locked position.

The lock presently to be described is designed more particularly for use in automobile doors and in the drawing the door part is designated by the letter A while the frame or jamb part is designated by the letter B. The jamb part is provided with a recess b and a keeper plate b' secured to the face of the jamb and having thereon intermediate its ends the bolt engaging part B². This part is conveniently formed of metal and has its intermediate portions bulged or crowned, as at B². It occupies when in position the rear part of the mortised or grooved out portion b of the jamb and is designed to receive thrusts of the locking bolt presently to be described.

The door A is mortised to receive a lock, frame C in which is pivotally mounted a rocking bolt D having as usual in such types of bolts, a curved face for entering through an opening in the frame and having a tail piece d opposite the locking face d'. The bolt is formed conveniently with a substantially straight rear face, as at d² in which is formed a tapered groove d³. This groove terminates on a plane below the pivot of the bolt, as shown in Fig. 8. In the curved face of the bolt there is provided a substantially V-shaped notch d⁴ in advance of the tapered groove d³.

Mounted on a vertically disposed shaft E journaled in the opposite side walls of the housing C is a setting and securing arm F for the pivot locking bolt. The end of the arm F is projected into the groove d³ of the locking bolt, as shown in Fig. 8, and is normally moved to an inward position,

as shown in said figure, by a spring F', the latter engaging the outer face of the arm and being coiled around the shaft E, as shown in Fig. 5. The tendency of the 5 spring is to carry the end of the arm into positive engagement with the straight surface at the bottom of the groove d^3 of the locking bolt and thereby force the locking face of the bolt directly into engagement with the part B² of the keeper. This is 10 acquired by having the end of the arm engage the bolt below the pivot thereof. The action manifestly is progressive in that the bolt is forced against the keeper by the 15 end of the arm moving over the surface with which it contacts. This insures a positive engagement and results in an anti-rattler being provided and maintains the two locking surfaces in positive engagement 20 at all times. To permit the door to be opened it is only necessary to move the shaft E downward.

With this in view the lower end of the shaft is provided with a diagonal groove or 25 camway e in which a pin e' on the hub of the arm F loosely plays. The shaft is held against rotation by means of a pin E' slidably mounted in suitable sockets E² on the upper face of the door frame. The shaft is 30 provided with an operating head G and is surrounded at its lower end by a spring G' abutting a shoulder or collar on the shaft at one end and the lock housing at the other end. The shaft has a free play up and 35 down. By virtue of the cam e, the arm F is rotated so as to carry its point into or out of engagement with the rocking bolt. The construction described is clearly depicted in Figs. 5 and 8. In these figures it will be 40 noted that the V-shaped notch d⁴ is so positioned that as the end of the arm F engages the rear wall of the notch the arm operating spring F' will tend to force the point of the bolt into the housing and there 45 retain the same, as shown in dotted lines, Fig. 8.

As a modified form of structure there is shown in Fig. 1 a lock bolt H having a straight rear face h. There is a rocking bolt lock I having its end part arranged 50 fixedly on a vertically arranged shaft j mounted in the casing. The shaft j is arranged outwardly beyond the plane of the pivot for the bolt H and is so proportioned that upon the rocking of the part I outward it will engage the flat surface of 55 the bolt and cause its lock point to engage the keeper. The point of contact between the part I and the bolt will vary according 60 to the positions of the locking part thereof and the keeper, the arm being so constructed as to advance and take up any wear or variations that may exist. To secure this result a spring is associated with the shaft j 65 and tends to at all times maintain the same

in its outward position, as shown in Fig. 1. A convenient form of spring may be that shown in Fig. 2 wherein a reciprocating handle shank L is shown mounted in the door and surrounded by a coiled spring l. 70 This shank is provided with a handle l' which may be drawn out and in its movement operates a bell crank M rigid on the shaft. The spring normally tends to move the shaft in the position shown in full lines, 75 Fig. 2. The bell crank is also provided with an arm N having a finger piece N' on its outer end whereby the shaft j may be rocked from the inside through the finger piece, as well as from the outside of the 80 door from the handle l'. When the bolt H of the construction shown in Fig. 1 is fully withdrawn it is engaged by a small spring actuated friction pin O seated in the bolt and adapted with its outer end to engage a recess O' in the wall of the lock casing. This will hold the bolt in open position against the tension of the spring l to force the same into closed position.

In Fig. 6 a slightly modified form of 90 operating means is shown wherein the shaft E has a cross arm P thereon, one end of which is provided with a thumb piece p while the other end is loosely connected with a reciprocating thumb piece Q mounted in a suitable bearing on the outer face of the door. The thumb piece Q has a stem entering a perforation in the door and below the same is provided a spring R which serves to rock the cross head in the position 95 shown in Fig. 6 and the locking arm in position to lock the bolt closed. This construction enables the operation of the latch arm from either the inside or the outside 100 of the door.

In Fig. 4 is shown a modified form of construction whereby a beveled gear S is mounted on the top of the shaft E, the latter being normally rotated in one direction by a spring S'. To turn the shaft a complementary beveled gear S² is employed mounted on a countershaft or spindle T passing through the door. The opposite ends of the spindle are provided with handles T'. 110

By the above described construction, including the modified forms, it will be ascertained that the locking bolt is always set into close contact with the keeper and there held. It will be observed further that upon the actuation of the handle or the operating 115 part the arm will be released and the bolt can thereby be readily set back into unlock- 120 ing position upon the opening of the door. Inasmuch as the spring arm is always in contact with the bolt, as soon as the door is 125 closed the bolt being driven into locked position, the end of the spring arm following up the movement of the bolt will sustain it in its locked position and should there be any play between the bolt and its keeper, the 130

arm will advance and progressively take up such play or movement. The device may be very properly characterized as an anti-rattler.

5 The arc through which the securing arm moves is so related to the arc through which the pivoted bolt moves that the former will exert a pressure in the direction of closing or locking of the bolt at all times and even 10 beyond a straight or right angular position with relation to the keeper.

In the broader aspect of the case the invention may be carried out with the single spring, as suggested, in the modified forms, 15 as well as the two springs suggested in the construction shown in Figs. 5 and 8. The swinging action of the securing arm with its operative end arranged to engage the bolt is an important feature of this invention.

Having thus described the invention, what is claimed as new and desired to be secured by Letters Patent is:

1. In a lock of the character described, a 25 pivoted bolt member having means for causing the same to move to different locking positions and to unlocking position upon manual operation, and a spring operated bolt locking member comprising means for differentially engaging and locking the bolt in its different locking positions.

2. A lock including a rotary bolt, a spring actuated arm arranged in rear of the bolt for slidingly engaging the same to force the 35 bolt into proper locking position and for retaining the same in said position.

3. A lock including a rotatably mounted bolt, said bolt having at its rear a substantially straight portion and a spring actuated 40 arm for slidably engaging said portion to properly position the bolt in locking position and for securing the same in said position.

4. A lock including a rotatably mounted bolt member, said bolt member having a substantially straight rear edge part, a grooved part interposed between the edge part and the locking part thereof, and a 45 spring actuated arm pivotally supported and having its free ends arranged to engage the said straight part of the bolt to progressively advance the locking part of the bolt and to secure the same in position and also adapted to engage the grooved part of the 50 bolt to cause the locking part thereof to finish its rearward movement and to be there retained.

5. A lock including a rotatably mounted bolt member, the said bolt member having 55 a rear surface part arranged beyond the pivot thereof, and a spring actuated arm having a portion thereof arranged to engage said bolt part for setting the locking part of the bolt into proper locking position and for securing the same in said position.

6. In a door lock the combination with a pivoted rocking bolt member having a locking portion and a substantially straight rear portion, of a spring actuated pivoted locking arm arranged to progressively engage 70 said straight portion for moving the bolt into proper locked position and for retaining the same in said position, and means for swinging the said arm away from the bolt.

7. In a door lock and in combination a 75 rocking bolt, a spring actuated pivoted arm slidingly engaging the bolt for moving the same into locked position and for retaining the same in said position, and a spring actuated hand piece for rocking the arm out of 80 engagement with the bolt.

8. In a lock the combination with a swinging member, of a pivoted locking bolt thereon, a shaft, a swinging arm associated with the shaft adapted to engage and move the 85 bolt and to lock the same in holding position, and a spring associated with the shaft for operating the arm in one direction.

9. In a lock of the character described 90 the combination with a pivoted bolt member, a swinging arm arranged in rear of the bolt member and adapted to engage the rear edge thereof for progressively positioning the bolt member in locking position and for retaining the same in said position, a shaft 95 for operating the arm away from the bolt, a hand piece on the shaft, and a spring for normally positioning the arm in its active locking position.

10. In a lock of the character described 100 the combination with a pivoted bolt member, of a swinging arm member having its end positioned to slidably engage the rear of the bolt member for moving the bolt member in proper locking position and for retaining the same in said position, a shaft 105 member for operating the arm to cause the same to disengage the bolt, and a plurality of means arranged in different positions for operating the shaft member.

11. In a lock of the character described 110 the combination with a lock casing, of a bolt member pivotally supported in the casing, a spring actuated arm pivotally supported in the casing and having its end adapted to engage the bolt to move the same in its proper locking position and for retaining the same in said position, a shaft upon which the arm is mounted, a spring for operating the shaft, and means for limiting 115 the movement of the shaft during its operation.

12. In a lock of the character described 120 the combination with a casing, of a pivoted bolt member in the casing, a positioning and locking arm for engaging the rear of the bolt, spring means for normally setting the arm against the bolt, and means for removing the arm from engagement with the bolt 125 comprising a rocking shaft, a lever engag. 130

ing the shaft, and a plurality of means for operating said lever.

13. In a lock of the character described the combination with a lock frame and a pivoted bolt member therein, a swinging arm for engaging the bolt to move the same into proper locking position and for retaining the same in said position, a shaft on which the arm is mounted, a spring for normally pressing the arm into engagement with the bolt, and means for compressing the spring to release the arm from engagement with the bolt.

14. In a lock of the character described the combination with a lock casing, a pivot bolt mounted therein, a spring actuated arm for engaging the rear of the bolt and for setting and securing the same in proper locking position, a reciprocating shaft on which the arm is mounted, a spring on the shaft, and means interposed between the

shaft and the arm causing the arm to move away from the bolt upon the movement of the shaft.

15. In a lock of the character described, 25 the combination with a lock casing, a pivot bolt mounted therein, a spring actuated arm for engaging the rear of the bolt and for setting and securing the same in proper locking position, a reciprocating shaft on 30 which the arm is mounted, a spring on the shaft, and a cam interposed between the shaft and the arm causing the arm to move away from the bolt upon the movement of the shaft. 35

In testimony whereof I hereunto affix my signature in the presence of two witnesses.

JOHN F. WHITE.
